[57] CLAIM

The ornamental design for a hand held shower head, as shown and described.

DESCRIPTION

FIG. 1 is a left side perspective view of a hand held shower head showing our new design;

FIG. 2 is a top plan view thereof;

FIG. 3 is a front elevational view thereof;

FIG. 4 is a right side elevational view thereof;

FIG. 5 is a rear elevational view thereof;

FIG. 6 is a bottom plan view thereof.

The broken line drawing is for illustrative purposes only and form no part of the claimed design.
